CLAIM

The ornamental design for a lid for an egg carton, as shown and described.

DESCRIPTION

FIG. 1 is a top, front right side perspective view of a lid for an egg carton;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged detail view taken from the designation

8 on FIG. 1; and,

FIG. 9 is an enlarged detail view, taken from the designation

9 on FIG. 1.

(Continued)

The evenly broken lines represent portions of the article that form no part of the claimed design. The dot-dot dash lines represent the designation of enlargement views and form no part of the claimed design.

1 Claim, 7 Drawing Sheets
